UNITED STATES PATENT OFFICE

JOHN W. CONNORS, OF DEDHAM, MASSACHUSETTS, ASSIGNOR TO THE REECE BUTTON HOLE MACHINE COMPANY, OF BOSTON, MASSACHUSETTS, A CORPORATION OF MAINE

BUTTONHOLE-SEWING MACHINE

Application filed September 27, 1926. Serial No. 137,888.

In each of United States Patents No. 1,497,215, June 10th, 1924 and No. 1,532,301, April 7th, 1925 is shown a buttonhole sewing machine constructed so that it will sew either a buttonhole with an eye at one end or a so-called "straight" buttonhole, that is, a buttonhole without an eye at the end. In buttonhole sewing machines of the type shown in said patents the stitch-forming mechanism is constructed to be rotated through a half circle at the end of the buttonhole and when the buttonhole is to be sewed with an eye at the end then the stitch-forming mechanism is continued in operation during its rotation around the end of the buttonhole and at the same time the stitch-forming mechanism and work are given a relative lateral movement which gives the eye shape to the end of the buttonhole. If a "straight" buttonhole is to be sewed then the stitch-forming mechanism is automatically rendered inoperative when one side of the buttonhole has been completed and remains inoperative while it is being turned around the end of the buttonhole and then is automatically rendered operative again for stitching the other side of the buttonhole.

The present invention relates to a buttonhole sewing machine of this type and has for one of its objects to provide improvements therein by which the buttonhole sewing machine may be used to sew either a buttonhole with an eye or a "straight" buttonhole as in the above-mentioned patents and in addition may be operated to sew an "imitation" buttonhole, this latter being simply one row of buttonhole stitches, as will be formed along one side only of the buttonhole.

Another feature of the invention relates to certain improvements by which the buttonhole may be sewed not only with an eye at the end but may be sewed around the end without forming the eye.

In order to give an understanding of my invention I have illustrated in the drawings a selected embodiment thereof which will now be described after which the novel features will be pointed out in the appended claims.

Fig. 1 is a side view of a sewing machine embodying my invention;

Fig. 2 is an under side plan view;

Fig. 3 is a fragmentary view of the devices for controlling the operation of the 55 stitch-forming mechanism to form either a buttonhole with an eye, a "straight" buttonhole or an "imitation" buttonhole;

Fig. 4 is a top plan view of the parts shown in Fig. 3 with them set in position to form a 60 "straight" buttonhole;

Fig. 5 is a similar view showing in full lines the parts set in position to form a buttonhole with an eye and in dotted lines set for forming an "imitation" buttonhole; 65

Fig. 6 is a fragmentary view showing the clutch for operating the stitch-forming mechanism and the means for disengaging the clutch;

Fig. 7 is a similar view showing the clutch 70 disengaged;

Fig. 8 is a view illustrating a "straight" buttonhole;

Fig. 9 is a view illustrating a buttonhole with an eye; 75

Fig. 10 is a view illustrating an "imitation" buttonhole;

Fig. 11 is a view illustrating a buttonhole sewed around the end but without the eye;

Fig. 12 is a fragmentary sectional view illustrating the means for giving the relative lateral movement to the stitch-forming mechanism and work-holding means for forming the eye; 80

Fig. 13 is a similar view showing the parts 85 adjusted for forming the type of buttonhole shown in Fig. 11;

Fig. 14 is a section on the line 14—14, Fig. 13;

Fig. 15 is a fragmentary view showing the 90 operation of the dog for resetting the clutch;

Fig. 16 is a fragmentary view showing the carrier 52.

Buttonhole sewing machines are commonly constructed so that in sewing a buttonhole 95 in material 1 the sewing will start at one end 2 of the buttonhole slit 3 and will proceed along one side of the buttonhole to the opposite end thereby to form the stitches 4 and will then proceed along the opposite side 100

back to the starting point to form stitches 5. Buttonhole sewing machines which are adapted to form a buttonhole with an eye at the end are constructed so that the stitch-forming mechanism can rotate about a vertical axis and if a buttonhole with an eye 6 is to be formed as shown in Fig. 9 then after stitching down one side of the buttonhole the stitch-forming mechanism is turned through a half circle and at the same time the stitch-forming mechanism and work 1 are given a back and forth lateral movement thereby to form the stitches 7 around the eye 6. In case the buttonhole is not to have an eye but is to be a "straight" buttonhole, as shown in Fig. 8, then the stitch-forming mechanism will be rendered inoperative after forming the stitches 4 and while said stitch-forming mechanism is turning around the eye end of the buttonhole, the stitch-forming mechanism being started into operation again after making the turn thereby to form the stitches 5.

The sewing machines illustrated in the above-mentioned Patents 1,497,215 and 1,532,301 are constructed so as to sew the buttonhole either with or without the eye as shown in Figs. 8 and 9. The present improvement provides additional features by which the machine may be operated so as to sew a single line of buttonhole stitches 4 as illustrated in Fig. 10 corresponding to the line of stitches along one side only of the buttonhole.

The form of stitching shown in Fig. 10 constitutes what is referred to as an "imitation" buttonhole and is frequently used in connection with buttons on the sleeve of a coat or in other places where buttons are used simply for ornamental purposes in order to give the appearance of a buttonhole.

This so-called "imitation" buttonhole is secured by the provision of means which operate to render the stitch-forming mechanism inoperative after stitching down one side of the buttonhole and to maintain it inoperative during the remainder of the buttonhole cycle. The complete buttonhole cycle involves the relative movement of the stitch-forming mechanism to form the stitches on one side of the buttonhole, the turning of the stitch-forming mechanism around the end of the buttonhole, and the relative movement between the stitch-forming mechanism and work-holding means to return the parts to the original position.

The main features of the sewing machine herein illustrated are similar to those shown in United States Patents No. 655,637, August 7th, 1900 and No. 713,764, November 18th, 1902, as well as in the above-mentioned Patents No. 1,497,215 and No. 1,532,301.

The work to be stitched is supported in usual work-holding means comprising the clamp plates 8 which are pivotally mounted

on a stationary bed plate 9 and which operate to clamp the work against the bed plate. The stitch-forming mechanism is of the usual type comprising an upper and lower thread-handling mechanism. The upper thread-handling mechanism is in the form of a vertically-reciprocating needle 10 carried by a needle bar 11 which reciprocates in the overhanging arm 12 of a head or frame 13 that is mounted on the bed plate 9 so that it can move back and forth thereon and can also move laterally thereon. The under thread-handling mechanism (not shown) is carried on a turret 91 situated beneath the bed plate 9.

The stitch-forming mechanism including the turret and the needle bar 11 is arranged to be turned bodily about a vertical axis at each end of the buttonhole as usual in sewing machines of this type and as shown in the above-mentioned patents. This turning movement is secured through a vertical rock shaft 14 which carries at its upper end a segmental gear 15 meshing with a gear 160 associated with the upper thread-handling mechanism, said rock shaft having a similar segmental gear 92 meshing with a gear 93 on the turret which supports the under thread-handling mechanism, all as shown in said Patent No. 655,637. This rock shaft 14 is turned at each end of the buttonhole thereby to give a bodily turning movement to the stitch-forming mechanism.

The stitch-forming mechanism and work-holding means have a relative movement during the stitching along the sides of the buttonhole and in the machine herein shown this relative movement is provided for by moving the head 13 carrying the stitch-forming mechanism back and forth on the bed plate 9, such movement being derived from a suitable main cam 16 situated in a cam housing 17 which is rigid with the head or frame 13 all as shown in the above-mentioned patents.

The stitch-forming mechanism is driven from a shaft 18 by means of a pulley 19 which is loose thereon and which is clutched thereto by a clutch of the type illustrated in said Patent No. 713,764 and which comprises a clutch dog 20 (see Figs. 6 and 7), which is pivoted at 21 on a hub 22 which is fast on the shaft 18. The clutch dog 20 has a projection 23 formed thereon which is adapted to engage a suitable shoulder 24 formed on the pulley 19. This clutch dog is acted on by a spring 25' which normally holds it in operative position with the projection 23 in the path of the shoulder 24. So long as said projection engages the shoulder the shaft 18 will be coupled to the pulley 19 and will be rotated thereby.

The clutch is disengaged by releasing the projection 23 from the shoulder 24 and this is accomplished by bringing the clutch-disengaging member 25 into the path of movement of the tail 26 of the clutch dog so that

as said tail engages the member 25 it will be turned about its pivot 21 as shown in Fig. 7 thereby withdrawing the projection 23 from the shoulder 24.

5 The member 25 is yieldingly supported on a rocking member 27 which is mounted on a rock shaft 28 supported on the head 13, said member having rigid therewith a rearwardly-extending arm 29. During the operation 10 of the stitch-forming mechanism this rocking member 27 is held in its inoperative position shown in Fig. 6 by means of a latch 30 which is pivotally mounted at 31 on the head 13 and is adapted to engage a lug 32 carried by the 15 arm 29. When the member 27 is thus engaged by the latch the clutch disengaging member 25 will be held out of the path of movement of the tail 26 of the clutch dog.

The arm 29 is acted upon by a suitable 20 spring 33 which tends to swing said arm upwardly thereby carrying the member 25 into the path of movement of the tail 26 of the clutch dog 20. When, therefore, the latch is released from the lug 32, as shown in Fig. 7, 25 then the member 27 will be turned by the spring 33 thereby carrying the clutch-disengaging member 25 into the path of movement of the tail 26 of the clutch dog thereby disengaging the latter and bringing the stitch-forming mechanism to rest.

Fig. 6, therefore, illustrates the position of the parts when the stitch-forming mechanism is operating and Fig. 7 illustrates the position of the parts when the stitch-forming 35 mechanism has been brought to rest.

Sewing machines of this type are usually provided with means for releasing the latch 30 from the lug 32 at the completion of the buttonhole and in the construction herein shown this is accomplished by a projection or shoulder 34 formed on the bed plate 9 and situated to be engaged by a screw 35 carried in the lower end of the latch 30 when the stitching on the buttonhole has been completed, said screw being brought into engagement with the projection by the movement of the head or frame 13 as the stitching 5 is being completed.

Means are herein provided similar to that 50 illustrated in Patent No. 1,497,215 by which the latch 30 may be disconnected from the projection 32 after the side stitches 4 along the first side of the buttonhole have been sewed thereby to allow the clutch-disengaging member 25 to disengage the clutch dog 20 from the shoulder 24 as shown in Fig. 7 with the result that the stitch-forming mechanism 55 will cease to function while it is turning around the end of the buttonhole, and by 60 which the clutch dog may be released thereby to start the stitch-forming mechanism in operation again after it has turned around the end of the buttonhole so that the side stitches 5 on the buttonhole will be completed. Such 65 means comprise an arm or lever 36 which

is pivotally mounted at 37 on a stand 38 that is secured to the stationary bed plate 9. This arm or lever has a handle 39 extending forwardly therefrom by which it may be turned about its pivot. The handle carries a projection in the form of a screw 40 which is adapted to be brought into alignment with the upper end 41 of the latch 30 by a swinging movement of the lever 36. When the lever 36 is moved so that the projection 40 is in line with the end 41 of the latch 30 then during the feeding movement of the head 13, while the line of stitches 4 are being formed, said screw 40 will engage the upper end of the latch 30 as shown in Fig. 7 and will swing 75 the latter so as to disengage it from the projection 32 thereby causing the clutch dog to be disengaged. This screw 40 is adjusted so that the disengagement of the clutch will occur when the stitches 4 at the sides of the buttonhole have been completed and just before the stitch-forming mechanism begins to turn around the end of the buttonhole.

The device herein shown is also provided with means for causing the clutch dog 20 to be 80 re-engaged with the shoulder 24 after the stitch-forming mechanism has swung around the eye of the buttonhole so that the stitching will start again and form the side stitching 5 on the buttonhole as shown in Fig. 8.

The portion 42 of the lever 36 which rests on the stand 38 has a dog member 43 pivoted thereto at 44, said dog member being provided at its end with a laterally-extending finger 45. This finger normally rests on a 90 curved spring plate 46 which is supported by the head 13. The arm 29, which carries the projection 32, has at its end a laterally-extending cam finger 47 which is provided with an inclined or cam face 48. Since the 95 dog 43 is carried by the swinging lever 36 said dog will be moved laterally by the swinging movement of said lever. When the lever is in the position shown in Fig. 4 the finger 45 of the dog 43 is in line with the cam projection 47 but when the lever 36 is swung into the position shown in Fig. 5 the finger 45 of said dog 43 is out of line with the 100 cam projection 47.

It will be remembered that the swinging 115 frame 27 and the projecting arm 29 are mounted on the moving head 13 and move back and forth with said head. During the forming of the stitches 4 on the buttonhole the head 13 is moving toward the rear of the 120 frame 9 or to the left in Fig. 3, and assuming that the lever 36 has been set for the forming of the "straight" buttonhole, as shown in Fig. 4, in which position the screw 40 is in line with the upper end 41 of the latch 125 30 and the finger 45 is in line with the cam projection 47, then as the line of stitching 4 is completed and just after the latch 30 has been released by the projection 40, the finger 45 of the dog 43 will ride up the inclined 130

face 49 of the resilient rest 46 and will be crowded between the incline 49 and the projection 47, the finger and projection at this time having the relative position shown in dotted lines, Fig. 15. This occurs while the stitch-forming mechanism is turning around the buttonhole but is not operating because the clutch dog 20 has been disengaged, and when the head 13 starts to move in the opposite direction to form the stitches on the second side of the buttonhole, the finger 45 will engage the cam face 48 and will ride over the projection 47.

The dog 43 is prevented from swinging upwardly during the time of its engagement with the cam face 48 by means of a stop pin 50 which is carried by the stand 38 and which extends through a lateral extension 51 rigid with the dog 43. When, therefore, the head 13 starts its return movement the engagement of the finger 45 with the cam face 48 will result in swinging the frame 27 downwardly thus retracting the clutch-disengaging member 25 from the tail of the clutch dog 25 and allowing the clutch to be thrown into operation thereby setting the stitch-forming mechanism in operation again.

The mechanism herein shown is constructed so that the latch-releasing screw 40 can be rendered operative to release the latch and thus cause the clutch dog 20 to be disengaged either when the finger 45 of the dog 43 is in its operative position, shown in Fig. 4, or when it is in its inoperative position, as shown in Fig. 5. Under the former conditions a "straight" buttonhole, such as shown in Fig. 8, will be formed. Under the latter conditions an "imitation" buttonhole, such as shown in Fig. 10, will be formed, because under these latter conditions the latch 30 will be released to stop the stitch-forming mechanism from operating when the "straight" line of stitches 4 have been completed but the clutch will not be re-engaged and will remain disengaged during the entire return movement of the head 13.

This is accomplished herein by mounting the pin 40 upon a swinging carrier 52 which is pivoted to the lever 36 at 53 so as to permit said carrier with the knock-off screw 40 to be swung from the full to the dotted line position Fig. 5, or from the full to the dotted line position Fig. 16.

When both the swinging lever 36 and the carrier 52 are in the full line position Fig. 5 then the parts are set for forming a buttonhole with an eye, as shown in Fig. 9, because the knock-off screw 40 is out of line with the end 41 of the latch so that the latch will not be released after the side stitching 4 has been completed, and the dog 43 is also out of line with the projection 47. If, however, while the lever 36 is in the position shown in Fig. 5 the carrier 52 is turned into the dotted line position, the knock-off screw 40 will then be

swung into position to engage the upper end 41 of the latch 30. As a result when the stitching 4 on the first side of the buttonhole has been completed the latch 30 will be released thereby causing the clutch dog 20 to be disengaged and the stitch-forming mechanism to be brought to rest but the clutch will not be re-engaged again after the stitch-forming mechanism has turned around the end of the buttonhole by reason of the fact that the dog 43 is out of line with the projection 47 and hence during the entire return movement of the head 13 the stitch-forming mechanism will be idle and the result will be that during the complete cycle of operations there will be formed simply a single line of buttonhole stitches 4 as shown in Fig. 10.

The swinging carrier 52 may be yieldingly retained in either of its two positions by means of a spring-pressed pin 54 which is adapted to enter either one of two notches depending on the position in which the carrier is placed. The portion 42 of the lever 36 also carries a spring-pressed retaining pin 58 which is adapted to drop into either one of two recesses formed in the stand 38 for yieldingly holding the lever 36 in either of the two positions shown in Figs. 4 and 5.

60 indicates stop pins that serve to limit the swinging movement of the lever 36.

The machine herein shown is also constructed so that the sewing around the end of the buttonhole may be done either in such a way as to form the eye 6, as shown in Fig. 9, or to form a buttonhole without an eye, as shown in Fig. 11. The eye is formed in the usual way by giving the head 13 a lateral movement while the stitch-forming mechanism is turning around the end of the buttonhole. This lateral movement is secured through the medium of a lever 61 which has a follower 62 that is adapted to be engaged in a cam groove 63 formed in the main cam 16. Said lever is fast on a post 64 journaled in suitable bearings 65 and the post has fast at its upper end an arm 66 carrying a shoe 67 which is received in a guideway or groove 68 formed in the stationary bed 9.

The cam groove 63 is so designed that it will give the lever 61 a to-and-fro swinging movement at the end of the buttonhole. Since the shoe 67 is held firmly from lateral movement in the groove 68 in the stationary bed plate 9 this swinging movement of the lever 61 will operate to give lateral movement to the head 13, all as described in the above-mentioned patents.

I have provided herein means whereby the lever 61 may be, at the will of the operator, rendered inoperative to give the head 13 its to-and-fro movement at the time that the stitching is being formed around the end of the buttonhole. This is accomplished herein by withdrawing the follower 62 from opera-

- tive engagement with the cam groove 63 and simultaneously locking the lever 61 from swinging movement. When this is done then the head 13 can only have a to-and-fro movement without any lateral vibration at the end of the buttonhole and the result will be that if the stitch-forming mechanism is in operation around the end of the buttonhole it will form stitches as shown at 69 in Fig. 11 thus producing a buttonhole stitched around the end but without the eye.
- As herein shown the follower 62 is in the form of a pin which is slidably mounted through the end of the lever 61 and is connected to a lever 70 pivoted at 72 to the operating lever 61. This lever 70 also has connected thereto an anchoring pin 73 which is adapted to engage in a recess 74 formed in the under side of the cam housing 17. The pins 62 and 73 are connected to the lever 70 on opposite sides of its pivot 72 and, therefore, when the lever is swung in one direction one of the pins will be projected and the other will be withdrawn and when the lever is swung in the opposite direction the position of the pins will be reversed. With the lever 70 in the position shown in Fig. 12 the follower pin 62 will be projected upwardly into the cam groove 63 while the anchoring pin 73 will be withdrawn from its recess 74. On the other hand, when the lever 70 is swung into the position shown in Fig. 13, the follower pin 62 is withdrawn from the groove 63 and the anchoring pin is projected into the recess 74. When the anchoring pin is thus in the recess 74 the lever 61 will be held from lateral movement and the head, therefore, will be permitted to move only in a straight line.
- The lever 70 is shown as acted on by a spring 75 which tends normally to hold the lever in the position shown in Fig. 12 and a spring latch 76 is provided for holding the lever in the position shown in Fig. 13.
- During the normal operation of the buttonhole sewing machine the lever 70 will be in the position shown in Fig. 12 and if a buttonhole with an eye is to be made the lever 36 will be moved into the position shown in Fig. 5 and the carrier 52 will be set in the full line position Fig. 5. If, however, a "straight" buttonhole such as shown in Fig. 8 is desired the lever 36 will be moved into the position shown in Fig. 4 with the result above described. If the "imitation" buttonhole shown in Fig. 10 is desired the lever 36 is swung into the position shown in Fig. 5 and the carrier 52 is moved into the dotted line position. If a buttonhole such as shown in Fig. 11 is desired then the lever 36 and carrier 52 are set in the full line position Fig. 5 and the lever 70 is swung into the position shown in Fig. 13. When the parts are in this position the stitching will continue from the starting point 2 of the buttonhole down one side

around the end and back to the point 2 again but the head 13 will have no lateral movement and, therefore, no eye will be formed at the end of the buttonhole.

I claim:

1. In a buttonhole sewing machine having stitch-forming mechanism and work-holding means arranged to have a forward and return movement relative to each other during each buttonhole cycle and in which the stitch-forming mechanism has a bodily turning movement about a vertical axis at the end of the buttonhole, the combination with said stitch-forming mechanism and work-holding means, of adjustable means adapted in one adjusted position to render the stitch-forming mechanism inoperative when the stitching has been completed on the first side of the buttonhole and while the stitch-forming mechanism is turning around the end of the buttonhole, and to render the stitch-forming mechanism operative again after it has made its half rotation, whereby a "straight" buttonhole is produced, and in another adjusted position to not only render the stitch-forming mechanism inoperative while it is turning around the end of the buttonhole, but also to maintain it inoperative throughout the remainder of the buttonhole cycle. 70
2. In a buttonhole sewing machine having stitch-forming mechanism and work-holding means arranged to have a relative forward and return movement during each buttonhole cycle and in which the stitch-forming mechanism has a bodily turning movement about a vertical axis at the end of the buttonhole, the combination with said stitch-forming mechanism and work-holding means, of means to render the stitch-forming mechanism inoperative when the stitching has been completed on the first side of the buttonhole and to maintain said stitch-forming mechanism inoperative during the remainder of the buttonhole cycle. 80
3. In a buttonhole sewing machine, the combination with stitch-forming mechanism and work-holding means, of means to produce a forward and return relative movement between the stitch-forming mechanism and work-holding means during each buttonhole cycle, and means to render the stitch-forming mechanism inoperative just before the completion of the forward relative movement and to maintain said mechanism inoperative during the entire return movement. 90
4. In a buttonhole sewing machine, the combination with stitch-forming mechanism and work-holding means, of means to produce a forward and return relative movement between the stitch-forming mechanism and work-holding means during each buttonhole cycle, and means actuated by said relative movement to render the stitch-forming mechanism inoperative just before the completion of the forward relative movement and to 100
- 110
- 115
- 120
- 125
- 130

maintain said mechanism inoperative during the entire return movement.

5. In a buttonhole sewing machine having stitch-forming mechanism and work-holding means arranged to have a relative forward and return movement during each buttonhole cycle, the combination with said stitch-forming mechanism and work-holding means, of adjustable means operative at the end of the forward relative movement to render the stitch-forming mechanism inoperative, and to render said mechanism operative again or to maintain it inoperative during the relative return movement depending on the adjusted 15 position of the adjustable means.

6. In a buttonhole sewing machine having stitch-forming mechanism and work-holding means arranged to have a relative forward and return movement during each buttonhole cycle, and in which the stitch-forming mechanism turns about a vertical axis at the end of the buttonhole, the combination with said stitch-forming mechanism and work-holding means, of adjustable means operated by said 20 relative movement at the end of the relative forward movement to render the stitch-forming mechanism inoperative while the latter is turning around the end of the buttonhole, and to render the stitch-forming mechanism 25 either operative again for the return relative movement or to maintain it inoperative during such return relative movement depending upon the adjusted position of the adjustable means.

35. 7. In a buttonhole sewing machine having stitch-forming mechanism and work-holding means arranged to have a forward and return relative movement during each buttonhole cycle, and in which the stitch-forming mechanism turns about a vertical axis at the 40 end of the buttonhole, the combination with said stitch-forming mechanism and work-holding means, of a clutch device through which the stitch-forming mechanism is actuated, and adjustable means operative in one 45 adjusted position to disengage the clutch after the stitching has been completed on the first side of the buttonhole, and then to cause re-engagement of the clutch after the stitch-forming mechanism has turned around the 50 buttonhole and in another adjusted position to disengage the clutch after the stitching has been completed on the first side of the buttonhole and without causing re-engagement of the clutch during the remainder of the buttonhole cycle.

8. In a buttonhole sewing machine having stitch-forming mechanism and work-holding means arranged to have a forward and return 60 relative movement during each buttonhole cycle, and in which the stitch-forming mechanism turns about a vertical axis at the end of the buttonhole, the combination with said stitch-forming mechanism and work-holding means, of a clutch through which 65

the stitch-forming mechanism is operated, an automatically operative clutch-disengaging member, a latch for holding the clutch-disengaging member inoperative, and adjustable means operative in one adjusted position to release the latch when the first side of the buttonhole has been completed and then to cause re-engagement of the clutch after the stitch-forming mechanism has made its half rotation about the end of the buttonhole, and in another adjusted position to release the latch when the first side of the buttonhole has been completed without causing re-engagement of the clutch during the remainder of the buttonhole cycle. 80

9. In a buttonhole sewing machine having stitch-forming mechanism and work-holding means arranged to have a relative forward and return movement during each sewing cycle and in which the stitch-forming mechanism turns about the end of the buttonhole, the combination with said work-holding means and stitch-forming mechanism, of means whereby the operator can, at will, cause the stitch-forming mechanism to cease 90 operation while it turns about the end of the buttonhole, and to begin operation again after such a turn or to cease operation at the end of the buttonhole and to remain inoperative during the remainder of the buttonhole cycle. 95

10. In a buttonhole sewing machine having stitch-forming mechanism and work-holding means arranged to have a forward and return relative movement during the buttonhole cycle and in which the stitch-forming mechanism turns around the end of the buttonhole, the combination with said stitch-forming mechanism and work-holding means, of a frame carrying said stitch-forming mechanism, a cam mounted on the frame for giving the stitch-forming mechanism and work-holding means said relative movement, means operated by said cam to give the stitch-forming mechanism and work-holding means a relative lateral movement while the stitch-forming mechanism is turning around the end of the buttonhole, and means to render the last-named means operative or inoperative at the will of the operator and to lock said means to the frame when it is inoperative. 110

11. In a buttonhole sewing machine having stitch-forming mechanism and work-holding means arranged to have a forward and return relative movement during the buttonhole cycle and in which the stitch-forming mechanism turns around the end of the buttonhole, the combination with said stitch-forming mechanism and work-holding means, of a frame carrying the stitch-forming mechanism, a cam mounted on the frame for giving the stitch-forming mechanism and work-holding means said relative movement, means operated by the cam to give the stitch-forming mechanism and work-holding 120

means a relative lateral movement while the stitch-forming mechanism is turning about the end of the buttonhole, a controlling lever by which said last-named means is rendered operative or inoperative at the will of the operator and by which said last-named means is locked to the frame when it is rendered inoperative.

12. In a buttonhole sewing machine having 10 stitch-forming mechanism and work-holding means arranged to have a relative forward and return movement during each sewing cycle, and in which the stitch-forming mechanism turns about the end of the buttonhole, 15 the combination with said stitch-forming mechanism and work-holding means, of a frame carrying said stitch-forming mechanism, a lever for producing a relative lateral movement between the stitch-forming mechanism and work-holding means while the former is turning about the end of the buttonhole, and means to render said lever inoperative at the will of the operator and simultaneously to lock it to the frame thereby locking 20 the stitch-forming mechanism and work-holding means from relative lateral movement.

13. In a buttonhole sewing machine having 25 stitch-forming mechanism and work-holding means arranged to have a relative forward and return movement during the buttonhole cycle and in which the stitch-forming mechanism turns about the end of the buttonhole, the combination with said stitch-forming mechanism and work-holding means, of a frame carrying said stitch-forming mechanism, a cam journaled in the frame, a lever actuated by the cam for giving 30 relative lateral movement to the work-holding means and stitch-forming mechanism 35 while the latter is turning about the end of the buttonhole, and means to disengage the lever from the cam and simultaneously lock said lever to said frame thereby locking the 40 stitch-forming mechanism and work-holding means from lateral movement.

14. In a buttonhole sewing machine having 45 stitch-forming mechanism and work-holding means arranged to have a relative forward and return movement during the buttonhole cycle and in which the stitch-forming mechanism turns about the end of the buttonhole, the combination with said stitch-forming mechanism and work-holding 50 means, of a cam for producing said relative movement, a lever, a follower pin carried by the lever and engaging the cam, means whereby the cam-actuated movement of the lever produces a relative lateral movement between 55 the stitch-forming mechanism and work-holding means, means to withdraw said follower pin from operative engagement with the cam, and means other than the follower pin to lock the lever from movement while 60 the pin is thus withdrawn.

15. In a buttonhole sewing machine having 65 stitch-forming mechanism and work-holding means arranged to have a relative forward and return movement during the buttonhole cycle and in which the stitch-forming mechanism turns about the end of the buttonhole, the combination with said stitch-forming mechanism and work-holding means, of a cam, a lever, a follower pin carried by the lever and engaging the cam, means whereby the cam-actuated movement of the lever produces a relative lateral movement between the stitch-forming mechanism and work-holding means, means to withdraw said follower pin from operative engagement with the cam, an anchoring pin movably carried by said lever and connected to said last-named means to be moved from its inoperative position to its operative position when the follower pin is withdrawn, and means co-operating with the anchoring pin when in its operative position to lock the stitch-forming mechanism and work-holding means from relative lateral movement.

In testimony whereof, I have signed my name to this specification.

JOHN W. CONNORS.
